Joseph Ibanez, New York, N. Y.

Application October 17, 1949, Serial No. 5,535

Term of patent 14 years

(Cl. D85—2)

To all whom it may concern:

Be it known that I, Joseph Ibanez, a citizen of the United States, residing in New York, in the county of New York and State of New York, have invented a new, original, and ornamental Design for a Combined Ash Tray and Glass Holding Unit, of which the following is a specification, reference being had to the accompanying drawing, constituting a part hereof.

Fig. 1 is a perspective view of a combined ash tray and glass holding unit, showing my new design,

Fig. 2 is a top plan view thereof with the drawer portion closed,

Fig. 3 is a front elevational view of Fig. 2,

Fig. 4 is a left hand end elevational view of Fig. 3, and

Fig. 5 is a right hand end elevational view of Fig. 3.

I claim:

The ornamental design for combined ash tray and glass holding unit, substantially as shown.

JOSEPH IBANEZ.
